UNITED STATES PATENT OFFICE

CIGARETTE PACKAGE

Henry M. Hoenig, Louisville, Ky.

Application September 1, 1939, Serial No. 293,118

9 Claims.

This invention relates to a package designed primarily for the packaging of cigarettes, but it is to be understood that a package, in accordance with this invention is for employment for the packaging of any articles of merchandise for which it may be found applicable.

As cigarettes are now packed, the package includes one or more outer wrappings of "Cellophane" for preserving the cigarettes. In order to withdraw a cigarette, the user necessarily opens the wrapping or wrappings of "Cellophane" and under such conditions the preservative qualities of the "Cellophane" with respect to the cigarettes are immediately destroyed. As a rule cigarette smokers remove the entire "Cellophane" wrapping from off the package and throw the same away, as it is a nuisance to try to keep "Cellophane" wrapping around the package once it has been opened and which results in the cigarettes, remaining in the package deteriorating from a state of freshness.

It is the aim of this invention to provide, in a manner as hereinafter set forth a cigarette package whereby at least half of the cigarettes therein will be sealed to the atmosphere to retain their freshness while the consumer has access to the others of the cigarettes to remove them from the package when desired.

The invention further aims to provide, in a manner as hereinafter set forth, a cigarette package including a pair of normally closed, independent, separately accessible inner containers arranged within outer wrappings, each for containing a division of the cigarettes of the package and with the containers formed of "Cellophane" for the purpose of retaining the cigarettes fresh until the containers are opened whereby the consumer can open one of the inner containers and then withdraw a cigarette therefrom when desired; and still have the other division of cigarettes in the other container sealed, protected and kept fresh until the said other container is opened.

The invention further aims to provide, in a manner as hereinafter set forth, separate means for independently and conveniently opening the aforesaid inner containers to permit of the removal of the cigarettes therefrom.

The invention further aims to provide, in a manner as hereinafter set forth, a cigarette package having the cigarettes therein arranged in a plurality of spaced bunches and including interiorly thereof an impervious means for retaining each of the bunches of the cigarettes fresh until access is had to the bunch and with the means snugly encompassing each of the bunches of the cigarettes for disposing one bunch separately of the other bunch.

The invention further aims to provide, in a manner as hereinafter set forth, a cigarette pack-

(Cl. 229—51) A cigarette package consisting of a pair of spaced inner containers of a size and shape to receive a bunch of cigarettes, each container being provided with an opening member for opening the same, a foldable blank for forming the containers and the opening members, and a means for sealing the containers to the atmosphere.

5

Embodying the aims aforesaid and others which may hereinafter appear, the invention consists of the novel construction, combination and arrangement of parts as will be more specifically referred to and illustrated in the accompanying drawings, wherein are shown embodiments of the invention, but it is to be understood that changes, variations and modifications may be resorted to which fall within the scope of the invention as claimed.

In the drawings:

Figure 1 is a perspective view of a cigarette package, in accordance with this invention with a part of the outer wrappings removed.

10 Figure 2 is a sectional plan of the inner containers and the opening members for the latter.

Figure 3 is a plan view illustrating the foldable blank employed to form the inner containers.

15 Figure 4 is a view similar to Figure 1 of a modified form of cigarette package in accordance with this invention.

Figure 5 is a view similar to Figure 2 of the inner containers of the modified form and the opening members for said containers.

20 Figure 6 is a plan view illustrating the form of foldable blank employed for setting up an inner container of the modified form.

Figure 7 is a cross sectional view of a modified form of coupled together inner containers.

25 Figure 8 is a plan view illustrating the foldable blank employed for setting up the modified form of coupled inner containers shown by Figure 7.

Figure 9 is a cross sectional view of still another modified form of coupled together inner containers.

30 Figure 10 is a plan view illustrating the foldable blank employed for setting up the modified form of coupled inner containers shown by Fig. 9.

Figure 11 is a cross sectional view of still another modified form of coupled together inner containers.

35 Figure 12 is a plan view illustrating the foldable blank employed for setting up the modified form of coupled together containers as shown by Figure 11, and

Figure 13 is an end elevation of a pair of inner containers of the form shown by Figure 9.

40 As is well known cigarette packages include a pair of wrappings, one encompassing the cigarettes, the other encompassing that wrapping which is about the cigarettes, and the said other wrapper is enveloped by an outer wrapping possessing protecting qualities for the cigarettes. This outer wrapping generally is formed of "Cellophane" and acts to retain the cigarettes fresh

until the package is opened. In a cigarette package in accordance with this invention the outer wrapping of "Cellophane" may or may not be employed.

With reference to Figure 1 a cigarette package 10, in accordance with this invention includes an outer wrapping or container 11 of any suitable material, an intermediate wrapping or container 12 of any suitable material, a pair of independent closed inner containers 13, 14, each adapted to contain a division or bunch of the cigarettes which are packed, and an independent opening, tearing-off, ripping or pull member 15 for each container. The inner containers 13, 14 are formed from a single web 16 of material possessing a characteristic to maintain the bunches of cigarettes fresh in the inner containers 13, 14 until the inner containers are open. Preferably the web will be formed of "Cellophane."

With reference to Figure 3 the web 16 is of rectangular form and provided transversely thereof with parallel spaced scores 17, 18, 19, 20, 21, 22, 23 and 24. The scores 17, 24 are spaced equi-distant from the side edges 25, 25' respectively of the web. The latter is also formed lengthwise thereof with parallel scores 26, 27 disposed parallel to and arranged in proximity to the lengthwise edges 28, 29 respectively of the web. The latter is also formed with rows 30, 31 of spaced V-shaped scores which extend outwardly from the scores 26, 27 to the edges 28, 29. The scores of the row 30 are oppositely disposed with respect to the scores of the row 31. The web 16 is also formed with two pairs of oppositely inclined spaced scores, and the inclined scores of one pair are indicated at 32 and those of the other pair 33. The pair of inclined scores are disposed outwardly of and spaced from the ends of said rows 30, 31. The inclined scores extend from the scores 17, 24 and the scores 26, 27 inwardly of the ends of the latter. The scores are provided in the web for the purpose of facilitating the folding of the web to provide the inner containers 13, 14 which are disposed in parallel relation. Before the web 16 is folded it has secured thereto the opening members 15 which are located on the inner and outer faces of the web, inwardly of and in proximity to the score 26, are oppositely disposed, arranged in inner end-wise spaced relation and extended from the side edges of the web, and when the latter is folded to provide the containers the members 15 are arranged on the inner and outer faces of the containers.

When the web 16 is folded the portion 34 thereof forms a part of the inner side walls of the containers. The remaining part of the inner side walls of the containers is provided by the portions 35, 36 of the web between the scores 26, 27, 17, 24 and side edges 25, 25'. The portions 35, 36 provide free edges within the containers and such edges are the end edges of the web. The outer side walls of the containers are provided by the portions 37, 38 of the web 16 between the scores 26, 27, 18, 19, 22, 23. The front walls of the containers are formed from the portions 39, 40 of the web between the scores 26, 27, 17, 18, 21, 22. The rear walls of the containers are formed from the portions 41, 42 of the web between the scores 26, 27, 19, 20, 23, 24. The end walls of the container 13 are formed from the portions of the web indicated at 41', 42', 43, 44, 45, 46, 47, 48, 49, 50, 51, 52, 53, 54 arranged outwardly of the scores 26, 27 between the web side edge 25 and the score 20. The end walls of the container 14 are formed

from the portions 55, 56, 57, 58, 59, 60, 61, 62, 63, 64, 65, 66, 67, 68 of the web arranged outwardly of the scores 26, 27 and between the score 21 and web side edge 25'. The portions 35, 36 of the web 5 are to be secured to the front and rear of the portion 34 when the web is folded. The web portions 41', 43, 45, 47, 49, 51, 53 are to be secured together in overlapping arrangement, when folded to provide an end wall of the container 13. 10 The web portions 42', 44, 46, 48, 50, 52, 54 are to be secured together in overlapping arrangement, when folded to form the other end wall of the container 13. The web portions 55, 57, 59, 61, 63, 65, 67 are to be secured together in overlapping arrangement, when folded to form an end wall of the container 14. The web portions 58, 59, 60, 62, 64, 66 and 68 are to be secured together in overlapping arrangement, when folded to form the other end wall of the container 14. 15 The parts of the web portion 34 outwardly of the scores 26, 27 and between the web portions 53, 55 and the web portions 54, 56 are split as at 69 to form such parts into half portions 69^a, 69^b, 69^c, 69^d. The splits extend from the scores 26, 27 to the edges 28, 29 respectively. The half portion 69^a is folded with the web portions 41', 43, 45, 47, 49, 51, 53 to provide a part of an end wall of container 13. The half portion 69^b is folded with the web portions, 42', 44, 46, 48, 50, 52, 54 to provide a part of the other end wall of the container 13. The half portion 69^c is folded with the web portions 55, 57, 59, 61, 63, 65, 67 to provide a part of an end wall of the container 14. The half portion 69^d is folded with the web portions 58, 59, 60, 62, 64, 66, 68 to provide a part of the other end wall of the container 14. When the containers 13, 14 are formed the extended portions 70 of the members 15 projecting in opposite directions from the inner side walls of the containers 13, 14 to provide for convenient access thereto by the consumer for selectively opening an inner container by severing off that portion of the container arranged outwardly of a member 15. 20 25 30 35 40 45 50 55 60 65 70 75

The bunches of the cigarettes are indicated at 71, 72 and each bunch preferably will contain ten cigarettes. One of the opening members 15 is secured to the inner faces of the web portions 35, 37, 39, 41 and has its portion 70 seating against the side edge 25 of the web, arranged against the outer face of web portion 35 and further arranged against the outer faces of the front and outer side walls of container 13 and in this connection attention is directed to Figure 2. The other opening member 15 is secured to the inner faces of the web portions 36, 38, 40, 42 and has its portion 70 seating against the side edge 25' of the web, arranged against the outer face of web portion 36 and further arranged against the outer faces of the rear and outer side walls of the container 14 and in this connection attention is directed to Figure 2. When the portions of the web, which provide the end walls of the containers are secured together and the portions of the web forming the inner side wall of the containers are secured together the containers will be sealed; and owing to the protective qualities, for the cigarettes possessed by the material from which the inner containers are formed the cigarettes will retain their freshness until the containers are opened for the purpose of removing the cigarettes. It is well-known that the wrappings 11, 12 have each of their end terminal portions folded and secured together to provide what may be termed end walls arranged in superim-

posed relation. The end walls of the wrapper 12 are disposed in superimposed relation with respect to the end walls of the inner containers.

It is readily obvious that the construction of the cigarette package 10 provides for retaining the cigarettes of one bunch fresh, while the consumer is using the cigarettes of the other bunch.

The opening or pull members 15 each act, when pulled for severing off a portion of an inner container to open the latter to permit of access to the cigarettes of a bunch. That portion of the member 15 arranged within a container is fixedly anchored thereto and the other portion when pulled will act to sever off a portion of the container.

With reference to the modified form of cigarette package 73 shown by Figures 4, 5 and 6 it includes the wrappings or containers 11, 12 and a pair of inner containers 74, 75 for receiving bunches 76, 77 respectively of cigarettes. The package 73 possesses the same advantages as the package 10. The difference between the package 73 and package 10 resides in setting up the inner containers 74, 75 free of each other, that is to say they are not connected together as the inner containers 13, 14 of the package 10. The containers 74, 75 are provided with oppositely disposed opening members 78 of the same form as the members 15.

Each inner container of the package 73 is formed from a foldable web 79 of a material possessing the same characteristics as the web 16. The web 79 may be of square or rectangular contour and as shown by way of example as square. The web 79 is formed with a pair of spaced parallel transversely disposed scores 80, 81 extending from the web edge 82 to web edge 83 arranged inwardly of and disposed in proximity to web edges 84, 85 respectively. The web 79 is also formed with spaced parallel horizontal scores 86, 87, 88 and 89 extending from score 80 to score 81. The scores 86, 89 are spaced inwardly of and in proximity to web edges 82, 83 respectively. The web 79 outwardly of the scores 80, 81 is formed with rows 90, 91 respectively of spaced V-shaped scores. The scores of the row 90 are oppositely disposed with respect to the scores of the row 91. The web includes spaced correlated portions 92, 93 between the scores 86, 89 and the said edges 82, 83 and between the scores 80, 81 to form the inner side wall of a container 74 or 75 when the web is folded; a portion 94 between the scores 80, 81, 87, 88 to form the outer side wall of a container 74 or 75 when the web is folded; a portion 95 between the scores 80, 81, 86, 87 to form the rear wall of a container 74 or 75 when the web is folded; a portion 96 between the scores 80, 81, 88, 89 to form the front wall of a container 74 or 75 when the web is folded; portions 97, 98, 99, 100, 101, 102, 103, 104, 105 outwardly of the score 80 to form an end wall of the container 74 or 75; and portions 106, 107, 108, 109, 110, 111, 112, 113, 114 outwardly adjacent the score 81 to form the other end wall of the container 74 or 75 when the web is folded. When the portions 92, 93 are in inner end wall forming position they are disposed in overlapping relation and are to be secured together. When the web portions 97 to 105 are in end wall forming position they are arranged in superimposed relation and secured together. When the web portions 106 to 114 are in end wall forming position they are arranged in superimposed relation and secured together.

Secured to the inner face of each web inwardly

of and in proximity to score 80 is a part of the length of one of the opening members 78. The member 78 which is associated with the container 74 is to have a part of the length secured to the inner faces of web portions 92, 94, 95, 96 and the remaining part of its length extend from web edge 82. The member 78 which is associated with the container 75 is to have a part of its length secured to the inner faces of web portions 93, 94, 95, 96 and the remaining part of its length extend from the web edge 83. This manner of securing the members 78 to the webs 79 provide for oppositely disposing them relative to the containers 74, 75. The extended portions of the members 78 are indicated at 115. When the container 74 has been completed the extended portion 115 of the member 78 associated therewith will be arranged against the outer face of web portion 93 and the outer faces of the front and outer side walls of said container. When the container 75 has been completed the extended portion 115 of the member 78 associated therewith will be arranged at the outer face of web portion 92 and the outer faces of the rear and outer side walls of container 75.

Preferably the members employed for opening the inner containers will be of fabric of ribbon-like form, but it is to be understood that they may be of any suitable form desired.

With reference to the modified form of pair of inner containers 116, 117 shown by Figure 7, they are set up from a blank (Figure 8) of substantially the same form as the blank shown by Figure 3 with the following exception. The blank or web shown by Figure 8 is indicated at 118 and it is not formed with the oppositely extending splits 69 in the parts 119 of the web portions 34 outwardly of the scores 26, 27 and between the web portions 53, 55 and the web portions 54, 56. The said parts 119 of the web portions provide couplers for connecting the containers 116, 117 together. The tear members employed in connection with the blank or web 118 are arranged in the same manner as the tear members 70. Parts of the form shown by Figures 7 and 8 which correspond to parts of the form shown by Figures 1, 2 and 3 are provided with corresponding reference characters.

With reference to Figure 10, it illustrates the foldable blank or web 120 from which the modified form of inner containers 121, 122 (Figure 9) are constructed. The lengthwise edges of the web are designated 123, 124 and its end edges at 125, 126. The web 120 is formed with a pair of lengthwise extending parallel scores 127, 128 arranged between the longitudinal median and the said edges 123, 124 respectively. The web 120 in proximity to the said edges 125, 126 is formed with spaced parallel transverse scores 129, 130 respectively which extend from the edge 123 to the edge 124. The web 120 is also formed with rows 131, 132 of oppositely disposed V-shaped scores between the transverse scores 129, 130. The scores 131 extend from the score 127 to edge 123. The scores 132 extend from the score 128 to edge 124. The end scores of the rows 131, 132 are spaced from the scores 129, 130. The web 120 is also formed with spaced parallel transverse scores 133, 134, 135, 136, 137 and 138 which extend from the score 127 to the score 128. The web 120 at one end terminal portion thereof is provided with a pair of oppositely inclined scores 139 which extend from the points of intersection of the score 129 with the scores 127, 128 to the corners 140 of the web. The lat-

ter is also formed at its other end terminal portion thereof with a pair of oppositely inclined scores 141, which extend from the points of intersection of the score 130 with the scores 127, 128 to the corners 142 of the web. The web is provided with a pair of oppositely disposed slits 143, 144. The slit 143 extends from the score 127 to the edge 123. The slit 144 extends from the score 128 to the edge 124. The slits 143, 144 are disposed on the transverse median of the web and are arranged centrally with respect to the central V-shaped scores of the rows of scores 131, 132. The web portion 145 between the scores 127, 128 and the score 129 and edge 125 corresponds in width and length to the web portion 146 arranged between the scores 127, 128 and the score 130 and edge 126. The web portion 145 forms a holding flap and a part of the container 121. The web portion 146 forms a holding flap and a part of the container 122. The web portion 147 between the scores 129, 133, 127, 128 corresponds in width and length to the web portion 148 between the scores 127, 128, 130, 138. The web portions 147, 148 are of greater width than the web portions 145, 146. The web portion 147 forms the inner side wall of the container 121. The web portion 148 forms the inner side wall of the container 122.

The web portion 149 between the scores 127, 128, 133, 134 corresponds in width and length to the web portion 150 between the scores 127, 128, 137, 138. The web portions 149, 150 are of greater width than the web portions 147, 148. The web portion 149 forms the rear wall of the container 121. The web portion 150 forms the rear wall of the container 122. The web portion 151 between the scores 127, 128, 134, 135 corresponds in width and length to the web portion 152 between the scores 127, 128, 136, 137. The web portions 151, 152 correspond in width and length to the web portions 147, 148. The web portion 151 forms the outer side wall of the container 121. The web portion 152 forms the outer side wall of the container 122. The web portion 153 between the scores 127, 128, 135, 136 corresponds in length to the said other web portions, but it is of materially greater width than the said other end portions. The web portion 153 forms not only the front walls of the containers 121, 122, but also constitutes a coupler between the said containers.

The slit 143 provides the web portions 154, 155 and the slit 144 provides the web portions 156, 157. The V-shaped scores 131 in connection with one of the scores 139, 141 and the scores 129, 130 and score 127 and edges 123, 125, 126 provide foldable web portions 158, 159, 160, 161, 162, 163, 164, 165, 166, 167, 168, 169, 170, 171, 172, 173, 174, 175.

The V-shaped scores 132 in connection with one of the scores 139, 141 and the scores 129, 130 and score 128 and edges 124, 125, 126 provide foldable web portions 176, 177, 178, 179, 180, 181, 182, 183, 184, 185, 186, 187, 188, 189, 190, 191, 192, 193.

The web portions 158 to 166 inclusive, when folded form one end of the container 121. When said end of the container 121 is formed the web portion 154 is folded against web portion 166. The web portions 158 to 166 are folded in overlapping relation and suitably secured together. The web portions 176 to 184 inclusive, when folded form the other end of the container 121. When the web portions 176 to 184 are folded the web portion 156 is folded against the web

portion 184, and such web portions 176 to 184 both inclusive are folded in overlapping relation and suitably secured together. The web portions 158 to 166 inclusive are folded inwardly on the score 127. The web portions 176 to 184 inclusive are folded inwardly on the score 128.

The web portions 167 to 175 inclusive, when folded form one end of the container 122. When said end of the container 122 is formed the web portion 155 is folded against web portion 167. The web portions 167 to 175 are folded in overlapping relation and suitably secured together. The web portions 185 to 193 inclusive, when folded form the other end of the container 122. When the web portions 185 to 193 both inclusive are folded the web portion 157 is folded against the web portion 185 and such web portions 185 to 193 are folded in overlapping relation and suitably secured together. The web portions 167 to 175 are folded inwardly on the score 127. The web portions 185 to 193 both inclusive are folded inwardly on the score 128.

Secured to the inner face of the web 120 in extending relation from the edges 125, 126 is a pair of oppositely disposed tear members 194, 195. Tear member 194 is for correlation with the container 121. Tear member 195 is for correlation with the container 122. When the web 120 is folded to provide the containers 121, 122 the members 194, 195 are not only arranged on the inner faces but also on the outer faces of said containers. The members 194, 195 are arranged in proximity to the score 127 and have their inner ends flush with the scores 135, 136. The modified form of containers 121, 122 are set up for the same purpose as the containers 13, 14 and access is had to the cigarettes in the containers 121, 122 in the same manner as access is had to the cigarettes in the containers 13, 14.

With reference to Figure 12, it illustrates a foldable blank or web 196 from which the modified form of inner containers 197, 198 (Figure 11) are constructed. The lengthwise edges of the web 196 are designated 199, 200 and the end edges at 201, 202. The web 196 is formed with a pair of lengthwise extending parallel scores 203, 204 arranged between its longitudinal median and the said edges 199, 200 respectively. The web 196 in proximity to the said edges 201, 202 is formed with spaced parallel transverse scores 205, 206 respectively which extend from the edge 199 to the edge 200. The web 196 is also formed with rows 207, 208 of oppositely disposed V-shaped scores between the transverse scores 205, 206. The scores 207 extend from the score 203 to the edge 199. The scores 208 extend from the score 204 to the edge 200. The end scores of the rows 207, 208 are spaced from the scores 205, 206. The web 196 is further formed with a pair of oppositely outwardly inclined scores 209, 210. The score 209 extends from the intersection of the scores 203, 205 to the corner 211 of the web 196. The score 210 extends from the intersection of the scores 204, 206 to the corner 212 of the web. The latter is formed with a pair of oppositely outwardly inclined scores 213, 214. The score 213 extends from the intersection of the scores 203, 206 to the corner 215 of the web. The score 214 extends from the intersection of the scores 204, 206 to the corner 216 of the web.

The web 196 is formed on its transverse median with a pair of oppositely extending slits 217, 218. The slit 217 is disposed centrally with respect to the central one of the V-shaped scores 207 and extends from the score 203 to the edge 199. The

slit 218 is disposed centrally with respect to the central one of the V-shaped scores 208 and extends from the score 204 to the edge 200.

The web 196 is provided with transversely disposed scores 219, 220, 221, 222, 223, 224, 225 which extend from the score 203 to the score 204.

The web portion 226 between the scores 203, 204, 205 and the edge 201 corresponds in width and length to the web portion 227 between the scores 203, 204, 206 and edge 202. The web portion 226 forms a part of the inner side wall of the container 197. The web portion 227 forms a part of the inner side wall of the container 198. The web portion 228 between the scores 203, 204, 205, 219 corresponds in length and width to the web portion 229 between the scores 203, 204, 206 and 225. The web portion 228 forms the rear wall of the container 197. The web portion 229 forms the rear wall of the container 198. The web portions 228 and 229 are of greater width than the web portions 226, 227. The web portion 230 between the scores 203, 204, 219, 220 corresponds in length and width to the web portion 231 between the scores 203, 204, 224, 225. The web portions 230, 231 are of less width than the web portions 228, 229. The web portion 230 forms the outer side wall of the container 197. The web portion 231 forms the outer side wall of the container 198. The web portion 232 between the scores 203, 204, 220, 221 corresponds in width and length to the web portion 233 between the scores 203, 204, 223, 224. The web portions 232, 233 correspond in width and length to the web portions 228, 229. The web portion 232 forms the front wall of the container 197. The web portion 233 forms the front wall of the container 198. The web portion 234 between the scores 203, 204, 221, 222 corresponds in width and length to the web portion 235 between the scores 203, 204, 222, 223. The web portions 234, 235 are of less width than the web portions 228, 229. The web portions 234, 235 correspond in width to the web portions 230, 231 and are of greater width than the web portions 226, 227. The web portion 234 forms the remaining part of the inner side wall of the container 197. The web portion 235 forms the remaining part of the inner side wall of the container 198. The web portions 234, 235 coact to provide a coupler for connecting or hinging container 197 to container 198. When the web is folded to provide the containers 197, 198 the web portions 226, 227 are arranged against the portion of the inner faces of the web portions 234, 235 and the said web portions 226, 227 are secured by a suitable cementitious material to the inner faces of the web portions 234, 235 whereby the said web portions 226, 227 coact with the web portions 234, 235 to provide the inner side walls of the containers 197, 198.

The scores 203, 205, 206, 207, 209 and 213 coact to form foldable web portions 236, 237, 238, 239, 240, 241, 242, 243, 244, 245, 246, 247, 248, 249, 250, 251, 252, 253.

The scores 204, 205, 206, 208, 210 and 214 provide foldable web portions 254, 255, 256, 257, 258, 259, 260, 261, 262, 263, 264, 265, 266, 267, 268, 269, 270.

The slit 217 in connection with the central score of the row of V-shaped scores 207 provide foldable web portions 271, 272. The slit 218 in connection with the central score of the row of V-shaped scores 208 provide foldable web portions 273, 274.

The web portions 236 to 244 both inclusive are foldable inwardly on the score 203 and in over-

lapping relation to provide one end of the container 197. The web portion 271 is folded against the web portion 244. When the web portions 236 to 244 are folded in overlapping relation they are suitably secured together. The web portions 254 to 261 are folded inwardly on the score 204 in overlapping relation to provide the other end of the container 197. The web portion 273 is folded against the web portion 261. When the web portions 254 to 261 are arranged to form the other end wall of the container 197 they are secured together by suitable cementitious material. The web portions 245 to 253 are folded inwardly on the score 203 in overlapping relation to provide an end of the container 198. The web portion 272 is folded against the web portion 245. When the web portions 245 to 253 are arranged in overlapping relation to provide an end of the container 198 they are secured together by suitable cementitious material. The web portions 262 to 270 are folded inwardly on the score 204 in overlapping relation to provide the other end of the container 198. The web portion 274 is folded against the web portion 262. When the web portions 262 to 270 are folded in overlapping relation to provide the said other end of the container 198 they are secured together by suitable cementitious material.

Secured to the inner face of the web 196 is a pair of oppositely extending openings or tear members 275, 276 and said members extend from the edges 201, 202. The inner end of the member 275 is flush with the score 221. The inner end of the member 276 is flush with the score 223. When the web 196 is folded to provide the containers 197, 198 the members 275, 276 are arranged on the inner and outer faces of the containers.

The construction shown by Figure 11 acts for the same purpose as the construction shown by Figure 2.

The inner containers are entirely separate and removable from the outer wrappings of the package, and when removed the cigarettes in each removed inner container will retain their freshness until such container has a portion thereof severed to permit of access to the cigarettes.

What I claim is:

1. In a cigarette package, a pair of normally sealed independently openable parallel closely related inner containers, each adapted for containing a quantity of cigarettes and including a front, a rear, a pair of end and inner and outer side walls, a severable enclosing means common to said containers, an independent opening member for each container having a portion anchored to the inner face of the latter in proximity to one of its end walls and a portion extended from within the container and disposed against and free of connection to the outer face of the body of the container, said containers being formed from a folded single web of material possessing the characteristic to maintain the cigarettes fresh in each container until the latter is opened, and the ends of one container being connected to the ends of the other container, the said portions of said members extended from the containers being oppositely disposed and passing outwardly between the inner side walls of the containers.

2. In a cigarette package, a pair of normally sealed independent parallel closely related openable inner containers, each adapted for containing a quantity of cigarettes and formed from a single web of material possessing a characteristic

to maintain the cigarettes fresh in each container until the latter is opened, said containers including inner side walls each formed of a pair of oppositely disposed overlapping sections, a severable enclosing means common to said containers, and pull members for selectively opening said containers, each of said members having a portion anchored to the inner face of and a portion extended outwardly from a container between the sections of the inner side wall of the latter and between a section of the inner side wall of both containers.

3. In a cigarette package, a pair of normally sealed closely related independently openable inner containers each adapted for containing a quantity of cigarettes, said containers being formed from a folded single web of material possessing a characteristic to maintain the cigarettes fresh in each container until the latter is opened, said web having inherent portions thereof disposed in correlated relation for coupling the containers together and constituting an inner wall common to said containers.

4. In a cigarette package, a pair of normally sealed closely related independently openable inner containers each adapted for containing a quantity of cigarettes, said containers being formed from a folded single web of material possessing a characteristic to maintain the cigarettes fresh in each container until the latter is opened, said web having inherent portions thereof disposed in correlated relation for coupling the containers together and constituting an inner wall common to said containers, and a severable enclosing means common to and completely concealing said containers.

5. In a cigarette package, a pair of normally sealed closely related independently openable inner containers each adapted for containing a quantity of cigarettes, said containers being formed from a folded single web of material possessing a characteristic to maintain the cigarettes fresh in each container until the latter is opened and including inner side walls, and said web having a folded portion, intermediate its ends constituting a coupling means between the containers and oppositely extending folded portions correlated with said coupling means providing said inner side walls.

6. In a cigarette package a pair of normally sealed inner containers each for receiving a quantity of cigarettes and having an inner side wall, said containers being independently severable at points inwardly of corresponding ends to completely remove an end terminal portion thereof and each possessing a characteristic to maintain the cigarettes therein fresh until an end terminal portion thereof is severed to provide for access to the cigarettes, oppositely extendible independently operable tearing-off means for the end terminal portions of the containers, said means having inner portions arranged within and secured to the inner faces of the containers, intermediate portions lying against and extended outwardly from said side walls and outer portions positioned against the outer faces of the containers, said means being located inwardly of corresponding ends of the containers, and a normally closed severable wrapper common to and completely concealing said containers and the outer portions of the said tearing-off means.

7. In a cigarette package a pair of normally sealed inner containers each for receiving a quantity of cigarettes and having an inner side

5 wall, said containers being independently severable at points inwardly of corresponding ends to completely remove an end terminal portion thereof and each possessing a characteristic to maintain the cigarettes therein fresh until an end terminal portion thereof is severed to provide for access to the cigarettes, oppositely extendible independently operable tearing-off means for the end terminal portions of the containers, said means having inner portions arranged within and secured to the inner faces of the containers, intermediate portions lying against and extended outwardly from said side walls and outer portions positioned against the outer faces of the containers, the outer portions of said tearing-off means being of a length to extend onto the outer faces of the outer sides of the containers, said means being located inwardly of corresponding ends of the containers, and a normally closed severable wrapper common to and completely concealing said containers and the outer portions of the said tearing-off means.

8. In a cigarette package, a pair of normally concealed connected together inner containers disposed in inner sidewise relation formed from a single web and each for receiving a quantity of cigarettes, said web having a portion thereof providing a coupling between the inner sides of said containers and having oppositely extending other parts thereof coacting with said coupling to form the inner side walls of the container and an edge within each container, said containers capable of being independently severed at points inwardly of corresponding ends to remove an end terminal portion thereof, said web possessing a characteristic to maintain the cigarettes in each container fresh until an end terminal portion is severed to provide for access to cigarettes, oppositely disposed independently operable tearing-off means for the end terminal portions of the containers, each of said means including an inner portion secured to the inner face of a container, an outer portion positioned against the outer face of said container and an intermediate portion bearing against one of said edges and disposed between one of said other parts and said coupling, said means being located inwardly from corresponding ends of the containers, and a normally closed severable wrapper common to and completely concealing said containers and the outer portions of said tearing-off means.

9. In a cigarette package, a pair of normally sealed connected together inner containers disposed in inner sidewise relation and formed from a single rectangular web having a pair of end edges each arranged in a container, each of said containers for receiving a bunch of cigarettes and capable of being independently severed at a point inwardly of one end to remove an end terminal portion thereof, said web possessing a characteristic to maintain the cigarettes in each container fresh until an end terminal portion of the container is severed to provide for access to a cigarette, oppositely disposed independently operable tearing-off means for the end terminal portions of the containers, each of said means including an inner portion secured to the inner face of a container, an intermediate portion overlapping an end edge of the web and an outer portion extended from the inner side of the container and arranged against the outer face of the latter, and a normally closed severable wrapper common to and completely concealing said containers and the outer portions of said means.

HENRY M. HOENIG.
